UNITED STATES PATENT OFFICE.

MARTIN PAYNE, OF TROY, NEW YORK.

THILL AND TRACE CONNECTOR.

SPECIFICATION forming part of Letters Patent No. 595,862, dated December 21, 1897.

Application filed April 28, 1897. Serial No. 634,227. (No model.)

To all whom it may concern:

Be it known that I, MARTIN PAYNE, a citizen of the United States, residing at Troy, in the county of Rensselaer and State of New York, have invented certain new and useful Improvements in Thill and Trace Connectors, of which the following is a specification.

My invention relates to devices for yieldingly connecting the thills of vehicles intended to be drawn by horses with the traces of the harness.

The object of my invention is to provide a simple, cheap, and durable thill and trace connector that may be advantageously substituted for the common whiffletree and whiffletree-hooks.

Each constituent element of my invention is described in detail, and its office, together with the mode of operation of the whole, fully explained hereinbelow.

Referring to the accompanying drawings, wherein like letters are employed to designate like parts throughout the several views, Figure 1 represents a vertical mid-sectional view of my invention attached to a thill, the means and method of joining the conductor to both thill and trace being shown. Fig. 2 represents an end view of the sliding hollow piston-thimble and hook. Fig. 3 represents a side view of the sliding hollow piston-thimble and hook and from the right-hand end of the piece held as in this figure the view drawn in the second figure was taken. Fig. 4 represents a top view of the parts delineated in the second and third figures, and Fig. 5 represents a top view of all the parts of my invention when properly assembled.

Considering Fig. 1, A designates a hollow casing, customarily cylindrical, having one closed end B, and provided exteriorly with projecting ears C and D, one placed at each end of the casing and both pierced by screw-holes, through which the casing may be screwed upon a thill. In practice ears C and D are occasionally placed upon the side of the casing instead of upon that portion directly opposite the trace-hook, (see also Fig. 5,) their positions being determined by the conditions and requirements of the purchasers.

E marks a longitudinal slot extending from the open end of casing A toward end B. The open end of casing A is interiorly

threaded, and a threaded stopper F closes the opening. Centrally located through stopper F is orifice f, which will be again mentioned. It is usual to form orifice f angular in cross-section in order that a tool having an end correspondingly shaped can be inserted in the orifice, whereby the stopper may be unscrewed or tightened. By following this plan of construction stopper F may fit flush with the casing end, thus adding to the compact appearance of the connector.

G marks the smoothly-bored interior of casing A, having all permissible length.

Letter H marks the sliding piston-acting thimble shown in all the views, particularly in Figs. 2, 3, and 4. Ordinarily a hollow cylinder, the thimble is fashioned to fit bore G closely, but movably.

J designates the closed end of the thimble and is pierced by a central orifice j. When thimble H and stopper F are in contact, orifices f and j complete a passage to the interior of the casing. Through the passage thus afforded the compressed air confined by the movement of the thimble escapes.

K marks the trace-hook, having projecting wings (see Fig. 2) and an orifice L. In Fig. 1 is shown one method of attaching a trace M to hook K. Through a longitudinal slit m in the trace the hook is passed and the trace turned to bring the wings of hook K across the cut. A latching-tongue N, attached to the trace, is then passed through orifice L to prevent accidental detachment of the trace. The expedients just described are very common and need no further attention here. Hook K and thimble H are joined by a block O, constructed to fit and travel in slot E. A slot-cover P is often formed integral with hook and thimble, but is not essential and may be dispensed with. (See Fig. 5.) The office of cover P is to prevent the entrance of solid particles likely to obstruct the operation of the invention.

Special attention is called to spring Q, coiled within and occupying approximately the entire inner length of the casing. It was with the intention of utilizing a spring of the greatest practicable length that the peculiar formation of parts hereinabove detailed has been devised. One end of spring Q abuts against the inner surface of end J of the thimble, the

remaining end of the spring meeting the inner surface of end B of the casing. All the available space is therefore occupied by the spring.

- 5 The mode of operation is believed to be indicated with sufficient clearness in the drawings. A pair of shafts require, of course, a pair of connectors, each yielding independently to the amount of pull upon the trace to 10 which it is attached. By properly proportioning the length of the piston-thimble no jamming in bore G results, and the length of spring Q affords as much play as it is possible to obtain in this class of devices.
- 15 I am aware that sliding spring-governed hooks with suitable casings are constructed and in use, but I have no knowledge of the existence of the special structure set out in my present application.
- 20 What I claim, and desire to secure by Letters Patent of the United States, is—
1. In a thill and trace connector, the combination of a suitable casing adapted to be fixed upon a thill, said casing having a lon-

gitudinal slot and an interior bore closed at 25 both ends, one of the end closures of said bore being removable, a hollow piston-thimble constructed to fit said bore movably, a trace - hook connected with the thimble through the slot in said casing, a spring, and 30 orifices opening into said casing, substantially as described.

2. In a thill and trace connector, the combination of the closed casing A adapted to be fixed upon a thill and having an interior bore 35 and perforated stopper F, said casing provided with a longitudinal slot, the hollow piston-thimble H having one open and one perforated end, the trace-hook K provided with a slot-cover and joined to said thimble through 40 said slot, and a coiled spring, substantially as described.

In witness whereof I hereunto set my hand in the presence of two witnesses.

MARTIN PAYNE.
